FLUID OPERATED ROTARY DRILLING BIT

Filed Aug. 29, 1938

UNITED STATES PATENT OFFICE

2,154,553

FLUID OPERATED ROTARY DRILLING BIT

John A. Zublin, Los Angeles, Calif.

Application August 29, 1938, Serial No. 227,277

18 Claims. (Cl. 255—71)

This invention relates to drilling tools, and more particularly to tools used in the rotary drilling of bore holes, such as oil wells, and still more specifically to hydraulic bits of the nature disclosed in my United States patent application No. 219,357, filed July 15, 1938, entitled "Combined fluid and rotary driven drill bits".

In the patent application referred to, utilization is made of the energy in fluid under pressure forced through a drill pipe for rotating the rotary cutting elements of the tool, reliance being had upon the reaction of the cutters on the formation to produce a rotation of a supporting member for the cutters. Circulating fluid is caused to issue through a plurality of circumferentially spaced nozzles for subsequent action directly upon the rotary cutter elements themselves, or by indirect action upon these cutters by causing the fluid to be guided by suitable blades formed on the supporting member or carrier for the cutters.

Limitations in space prevent appropriate positioning of all of the nozzles substantially in a single plane, as disclosed in the aforementioned patent application. The particular drilling tool described therein as a preferred embodiment has approximately one-half of its cutters in formation contact at any instant of time, the other half being out of contact, or in reserve. Those cutters contacting with the bottom of the hole are not acted upon during their entire period of contact by fluid issuing through the nozzles. There are times when no turning effort is being applied to the cutters to cause their rotation, so that through their reaction with the formation they can assist in the rotation of their supporting body or carrier with respect to the supporting shank.

The overcoming of this difficulty constitutes one of the objects of this invention. Accordingly, one of the features of the invention involves a hydraulic type of drilling bit embodying an improved arrangement of nozzles in order to obtain a better fluid distribution therethrough for action upon the roller cutters.

A further object of the invention is to provide a hydraulic type of drilling bit having a plurality of roller cutters, each cutter being acted upon with the full force of a jet of fluid issuing from a single nozzle or with partial forces of jets issuing from a plurality of nozzles so as to impart a continuous driving force to each cutter during the entire time it is in formation contact.

In the aforementioned application, the main bearing assembly for the cutter supporting body or carrier is complex and relatively difficult to manufacture. Accordingly, a further object of

the invention resides in an improved bearing assembly for a rotary drilling bit that is relatively easy to manufacture and put together, and which is possessed of greater load carrying capacity.

Another object of the invention is to decrease the resistance to flow of fluid through the bearing assembly.

This invention possesses many other advantages and has other objects that will become apparent from a consideration of an embodiment of the invention. For this purpose, a form is shown in the drawing accompanying and forming part of the present specification, which embodiment will now be described in detail, illustrating the general principles of the invention. However, it is to be understood that this detailed description is not to be taken in a limited sense, since the scope of the invention is best defined by the appended claims.

Referring to the drawing:

Figure 1 is an elevation of a combined digging and reaming bit, the digging portions being shown in section to illustrate details thereof.

Figure 2 is a view of the drill bit taken along the line 2—2 of Figure 1.

Figure 3 is a section taken along the plane 3—3 of Figure 1.

Figure 4 is an elevation of a modified form of cutter usable in the general tool organization.

In one of its aspects, the invention seeks to overcome the limitations imposed by the material in a nozzle assembly which prevent uniform distribution of the nozzles in a single plane in order that the jets of fluid can exert their kinetic energy upon the cutters to cause their rotation at all times while they are in contact with the formation. The difficulty noted can be overcome in the specific example shown in the drawing by providing a staggered arrangement of nozzles consisting of a plurality of rows, the nozzles in each row being substantially in the same plane. It is desirable that each nozzle be so positioned as to direct the fluid issuing therefrom onto substantially the same parts of each roller cutter.

The drilling tool shown is of the composite type described and claimed in my copending applications No. 191,621, filed February 21, 1938 and No. 218,491, filed July 11, 1938. It consists of a shank 10 having a tapered, threaded pin 11 at one end for its attachment to a string of drill pipe (not shown), a reaming portion A, and a digging portion B. The shank has a pair of depending legs 12, 13, one of which 12 is preferably formed integrally therewith and the other 13 detachably secured thereto for a purpose that will appear

later in the description. The integral leg 12 is provided with an integral transverse extension 14 functioning as part of a support for a main bearing sleeve 15 adapted to rotatably carry a cutter supporting body or carrier 16 through the intermediation of a plurality of ball bearings 17 rollable in complementary races 18, 19 formed respectively in the inner surface of the carrier and in the external surface of the bearing sleeve. One 10 end 20 of the bearing sleeve 15 fits snugly over the integral supporting extension 14, while its other end 21 is piloted into a recess 22 provided in the detachable leg 13. Additional support is given to the bearing sleeve by inserting therein a 15 plug 23 having a snug sliding fit with the inner surface 15a of the sleeve 15 and having a reduced outer end portion 23a providing an annular space 24 between it and the inner surfaces of the sleeve and a bore 25 formed at the lower end of the 20 detachable leg 13.

The carrier 16 is provided with two spaced wall portions 26, 27 between which extend bearing pins 28 for rotatably mounting the cutters 29. Each cutter is placed within a recess 30 provided 25 in the carrier, and its bearing pin 28 inserted through a hole 32 in one of the carrier walls 27, through a bore 31 in the cutter and then into a hole 32 in the other carrier wall 26, after which the bearing pin 28 can be rigidly and securely 30 attached to the carrier by welding in material 33 in the holes. With all of the cutters 29 thus mounted on the carrier 16, the latter member is then placed over the bearing sleeve 15 and the balls 17 inserted into the raceways 18, 19 through 35 the holes 34 extending from the inner sleeve bore to its external raceway. The cylindrical portions 35 of buttons 36 are then inserted in the holes 34 to provide a substantially continuous raceway on which the bearing balls 17 can roll and also to prevent their unwarranted removal 40 from the races. The assembly including the buttons is then placed over the integral supporting extension 14 with a rectangular button portion 37 positioned in a keyway 38 cut or otherwise formed in the extension.

The sleeve 15 makes a snug fit with the extension 14 in order that it will be held in proper alignment therewith. The cooperation between the rectangular button portion 37 and the keyway 38 in the extension will prevent rotation between the bearing sleeve 15 and the extension 14. For the purpose of insuring that such rotation will be impossible of occurring, a fillet 39 is welded between the end of the extension and the beveled surface 15b provided in the bearing sleeve.

Subsequent to the welding in of the fillet, the plug 23 is inserted in the bearing sleeve bore 15a. This plug is provided with a keyway 40 in which a rectangular button portion 37 can be received. Thereafter, the detachable leg 13 is placed over the end 21 of the bearing sleeve and its upper portion 13a integrated to the shank by welding in material 41 in a groove 42 formed between the end of the leg and the shank. Attachment of the sleeve 15 to this leg can be had by welding in material 24a in the annular groove 24 between the sleeve 15, leg 13 and reduced plug extension 23a.

The cutters 29 are to be rotated by the action of fluid impinging against the cutting teeth 29a or against suitable vanes, blades or buckets that can be attached to the cutters. For this purpose, a plurality of nozzles 43, 44 is provided in the bearing sleeve, being adapted to direct discharges of fluid against the cutters 29 and also against the

carrier 16 rotatably mounting the cutters. The fluid under pressure will be conveyed from suitable pumps at the surface of the bore through the usual string of drill pipe to a passageway 45 provided in the shank and extending into the leg 12 integral with the shank. From this passageway, the fluid can pass through a bore 46 in the bearing support 14 and thence into the interior of the bearing sleeve 15, from where it can make its exit through the nozzles 43, 44.

It will be noted that the plug 23 closes one end of the bearing sleeve to prevent leakage of fluid therebeyond and eliminate loss in pressure. In this action the plug is assisted by the welding material 24a in the annular groove 24. The proper flow between the shank, leg and bearing sleeve is also insured by making the inner bearing sleeve bore 15a of substantially the same diameter as the integral extension bore 46 and also coaxial therewith.

The positioning of the bearing sleeve 15 over the extension 14 permits the provision of a larger sleeve, and consequently, the use of a larger bore 15a therein. A greater volume of fluid with a lesser resistance to its flow can therefore be passed through the sleeve and into the nozzles 43, 44, to increase the capacity of the drill bit.

As explained in my application Serial No. 219-357, fluid will issue through the nozzles 43, 44 and act directly upon the cutter teeth 29a on each cutter 29, causing it to rotate on its bearing pin 28, and by virtue of its reaction with the formation produce rotation of the carrier 16 on the main bearing sleeve 15. The fluid from the nozzles will also act upon blades 47 formed on ribs 48 extending between the carrier walls 26, 27, which ribs serve to define the recesses 30 in which the cutters rotate. This impinging fluid urges carrier rotation with respect to the shank. From these blades 47, the fluid stream will be 40 guided onto the teeth or vanes of the cutter portions to assist in their rotation.

For efficient operation of the drilling tool, it is essential that adequate flow occur through each nozzle. Inasmuch as the drilling tool disclosed is 45 designed to operate similarly to an impulse type of turbine or water wheel, the fluid must have its pressure head changed to velocity head by causing its rate of flow to accelerate in its passage through the nozzles. Thus, the nozzle exit 50 areas 49 are much less than their entrance areas 50 which will produce an increase in velocity of the fluid passing through the nozzles. It will be noted further that the entrance areas cover a material circumferential extent of the inner bore 55 of the sleeve. This is essential because of the angle at which the nozzles must be placed for efficient and effective discharge of fluid onto the cutters 29 and the blades 47 formed on the carrier. Because of this material circumferential 60 extension of the nozzle entrance area 50, the number of nozzles that can be placed in a single plane on the sleeve is limited to such an extent that fluid issuing under a high velocity from the nozzles cannot be acting upon each cutter during its 65 entire period of rolling contact with the bottom of the hole, which, in the specific instance disclosed, will be for about 180° of each complete revolution of the carrier. This difficulty is overcome in accordance with the present invention by 70 providing a plurality of rows 43, 44 of nozzles, the nozzles 43 of one row being staggered with respect to the nozzles 44 of another row, and preferably arranged so that there are substantially 75 equal circumferential spacings between the noz-

zles in one row and those in the other row. By virtue of this arrangement, assurance is had that one or more jets of fluid will be acting upon each cutter during its entire contact with the bottom of the hole.

The operation of the nozzles, cutters and carrier can possibly be better understood by tracing a cycle through which one of the cutters passes. As seen in Figure 2, the carrier 16 is rotating clockwise and by reason of their contact with the formation the cutters 29 will be rotating counter-clockwise. Fluid issuing from nozzle 44a will first engage against the blade 47a formed on the carrier, from which it will be guided and deflected onto the cutter teeth 29a to cause rotation of the cutter 29. As the carrier continues its rotation, the carrier blade will eventually move out of the line of action of the nozzle 44a which will then direct the full force of its issuing fluid through the carrier passageway 16c directly onto the cutter teeth. Continued rotation of the carrier will eventually move the cutter from the line of action of the nozzle 44a. But before this occurs, fluid from the nozzle 43a in the other row will be directed onto the carrier blade 47a for causing carrier rotation and also guidance of the fluid onto the cutter teeth. This is aptly illustrated by the relative positions of the nozzles 44a and 43a with respect to the carrier passageway 16d, its blade 47b, and the cutter 29. In this position, part of the fluid from the nozzle 44a is acting directly upon the cutter teeth and the fluid from the other nozzle 43a is acting directly upon the carrier blade 47b, where it will lose part of its kinetic energy, the blade guiding the fluid for action upon the cutter teeth to which it will impart the remainder of its energy. Continued rotation of the carrier will alternately bring the cutter into positions under the other nozzles 44b, 43b, 44c in which it will receive the full force of fluid from one of them, and upon moving from the line of action of that particular nozzle it will then be acted upon by partial streams of fluid issuing from more than one nozzle. The net result is to provide a more uniform application of fluid energy to the cutters while they are in formation contact.

After passing through 180° of contact with the formation, each cutter will leave the hole bottom and pass to an upper position. As there is no need for rotating the cutters while they are out of formation contact, the upper part 15e of the bearing sleeve 15 is circumferentially continuous, no fluid being permitted to pass to the cutters when in this position. This renders the entire fluid pressure available for action upon the cutters while they are in formation contact.

The nozzles 44 in one row are preferably inclined with respect to the nozzles 43 of the other row, the inclinations 51, 52 being toward one another. This arrangement is preferred because the fluid streams from both rows of nozzles will then act upon substantially the same portion 29a of each cutter so as to obtain a smoother operation and also centralize any erosion on the cutter teeth caused by the fluid jets.

When in operation, the cutters and carrier will be rotated by the action of the fluid stream. However, the rolling of the cutters on the formation will effect its removal but it will also tend to produce a groove of semi-circular longitudinal section equal in length to the roller cutters. For the purpose of insuring that a full gauge hole will be produced, the string of drill pipe and the shank attached thereto are also rotated so that the

cutters assume an infinite number of planes of rotation to provide a corresponding number of semi-circular grooves which will all combine to produce a hemispherical hole bottom of the proper radius. Rotation of the string of drill pipe will also prevent its freezing in the bore.

In Figure 4, a modified form of roller cutter is disclosed, including a toothed portion 29a and end, disc portions 29b. The fluid discharges from the nozzles will engage the toothed portion 29a to rotate the cutters, as heretofore described, such rotation causing the discs to dig into the formation to cut many narrow grooves therein and thereby effect its removal. This type of cutter presents a lesser area to the formation so that it can be penetrated with lighter drilling weights.

The upper part A of the drilling tool constitutes a reamer, described in detail and claimed in my co-pending application Reamer, Serial No. 227,-278, filed August 29, 1938. For the purpose of this application it is sufficient to merely call attention to the reamer roller cutters 55 rotatably mounted on the bearing supporting pins 56 welded to the plates 57, which, in turn, are welded to the shank 10. The cutters 55 are kept free from cuttings by streams of fluid issuing through the nozzles 58 communicating with the shank passageway 45.

I claim:

1. In an earth boring apparatus, a shank, cutter means rotatably mounted on the shank, and fluid discharge means within the cutter means supported by said shank, said fluid means including a plurality of rows of nozzles adapted to direct their discharges against the same portions of said cutter means to cause its rotation.

2. An earth boring apparatus as defined in claim 1, the nozzles of one row being staggered with respect to the nozzles of another row.

3. In an earth boring apparatus, a shank, rotational means including a carrier rotatably mounted on the shank and a plurality of cutters rotatably mounted on said carrier, and fluid discharge means within the carrier supported by said shank, said means including a plurality of circumferentially arranged rows of nozzles adapted to direct their discharges against said rotational means to cause rotation of said cutters and carrier.

4. An earth boring apparatus as defined in claim 3, the nozzles of one row being staggered with respect to the nozzles of another row.

5. An earth boring apparatus as defined in claim 3, the nozzles of one row being staggered with respect to the nozzles of another row, and having their lines of action inclined with respect to the lines of action of said last-mentioned row of nozzles.

6. In an earth boring apparatus, a shank carrying a bearing sleeve, a carrier rotatably mounted on said sleeve, a plurality of cutters rotatably mounted on said carrier, a fluid passageway in said shank, a fluid passageway in said sleeve communicating with said shank passageway, and a plurality of nozzles arranged in rows in the sleeve opening outwardly around the periphery thereof and communicating with its passageway, the nozzles of adjacent rows being staggered with respect to one another and being adapted to direct their discharges against said cutters to cause their rotation.

7. In an earth boring apparatus, a shank carrying a bearing sleeve, a carrier having a plurality of blades thereon rotatably mounted on said sleeve, a plurality of cutters rotatably

- mounted on said carrier, a fluid passageway in said shank, a fluid passageway in said sleeve communicating with said shank passageway, and a plurality of nozzles arranged in rows in the 5 sleeve opening outwardly around the periphery thereof and communicating with its passageway, the nozzles of adjacent rows being staggered with respect to one another and being adapted to direct their discharges against said carrier 10 blades to cause carrier rotation.
8. The combination defined in claim 6, the nozzles of one row being inclined toward the nozzles of another row in a direction outwardly of said sleeve.
15. 9. The combination defined in claim 7, the nozzles of one row being inclined toward the nozzles of another row in a direction outwardly of said sleeve.
10. An earth boring tool including a shank 20 having a bearing supporting extension, a bearing sleeve piloted within said shank and encompassing said extension, and cutter means rotatably carried by said sleeve.
11. An earth boring tool including a shank 25 having a bearing supporting extension, a bearing sleeve within which said extension is piloted, means within said sleeve for securing it to said shank, and cutter means rotatably carried by said sleeve.
30. 12. An earth boring tool including a shank having a bearing supporting extension, a bearing sleeve piloted within said shank and encompassing said extension, means within said sleeve for securing it to said shank, and cutter means rotatably carried by said sleeve.
35. 13. An earth boring tool including a shank having a bearing supporting extension, a hollow bearing sleeve piloted within said shank and encompassing said extension, means including a 40 plug within said sleeve for securing it to said shank, and cutter means rotatably carried by said sleeve.
45. 14. An earth boring tool including a shank having a bearing supporting extension, a hollow bearing sleeve piloted within said shank and encompassing said extension, means for securing said sleeve to said extension, means including a plug within said sleeve for securing it to said 45
- shank, and cutter means rotatably carried by said sleeve.
15. An earth boring tool including a shank having a bearing supporting extension, a hollow bearing sleeve encompassing said extension, said 5 sleeve having a plurality of raceways thereon, cutter means having a plurality of complementary raceways, rolling bodies in said raceways, means within said sleeve for preventing removal of said rolling bodies, said means securing said sleeve to said extension to prevent its rotation with respect thereto.
16. An earth boring tool including a shank having a bearing supporting extension, a hollow bearing sleeve encompassing said extension, said 15 sleeve having a plurality of raceways thereon, cutter means having a plurality of complementary raceways, rolling bodies in said raceways, means including a plug within said sleeve for securing it to said shank, means within said 20 sleeve for keying it to said extension, and means within said sleeve for keying it to said plug, both of said last-mentioned means extending to said raceways for maintaining said rolling bodies thereon.
17. An earth boring tool including a shank having a bearing supporting extension, a hollow bearing sleeve encompassing said extension, cutter means rotatably carried by said sleeve, a fluid 25 passageway in said shank and its extension communicating with said hollow bearing sleeve, and a plurality of nozzles in said sleeve extending to its interior, whereby fluid discharge from said nozzles against said cutter means will cause their rotation with respect to said sleeve.
30. 18. An earth boring tool including a shank having a bearing supporting extension, a hollow bearing sleeve encompassing said extension, cutter means rotatably carried by said sleeve, a fluid passageway in said shank and extension communicating with said hollow bearing sleeve, a plug closing the end of said sleeve to prevent leakage therebeyond, and a plurality of nozzles in said sleeve extending to its interior, whereby fluid discharge from said nozzles against said 35 cutter means will cause their rotation with respect to said sleeve.

JOHN A. ZUBLIN.
